Howson and Howson

UNITED STATES PATENT OFFICE

HARRY B. LEWIS, OF BROOKLYN, NEW YORK, ASSIGNOR TO BOORUM & PEASE COMPANY, OF BROOKLYN, NEW YORK, A CORPORATION OF NEW YORK

LOOSE LEAF RING BOOK

Application filed November 23, 1929. Serial No. 409,395.

This invention relates to loose leaf ring books and more particularly to those having a plurality of rings which are complete and pass loosely through the two covers of the book. It has been discovered that with this type of book the various rings are apt to turn longitudinally of the back of the book at various angles relative to each other which makes it hard to open the book or to turn the 10 sheets in the book when it is opened. The object of this invention is to insure that the rings will always lie in parallel planes thus making it possible at all times to turn the sheets or cards in the book from one side to the other of the book without jamming or 15 tearing the leaves.

In the drawings:

Figure 1 is a side elevation of a closed loose leaf ring book embodying the invention.

Figure 2 is a vertical section of the book shown in Figure 1 on a line corresponding to 2—2, but showing the book opened and showing in dotted lines one leaf being turned 25 from one side of the book to the other.

The ordinary loose leaf ring book consists of two covers 7, having openings 8 in one longitudinal edge thereof to receive rings 9, which are otherwise completely free or detached from said covers. The sheets 10 in the binder are threaded on these rings 9, the rings being hinged for this purpose.

It will be noticed that with this ordinary construction the rings can flop in opposite 35 directions and that when the binder is open this flopping will vary the distance between the rings at the points where they pass through the sheets, thus causing the sheets to be torn or jammed if an attempt is made 40 to turn the sheet from one side to the other.

This tearing or jamming effect is particularly undesirable when the covers of the ring book are turned apart with an angle of less than 180° between them, to form a stand, and the 45 sheets are moved over the rings through an arc of more than 180° in turning from page to page. Such a position is shown in the drawings at Fig. 2, the covers being turned apart until they form an angle of 50 less than 90° between their outer sides. The

covers are held at this angle by a chain 11 which may be permanently attached to one cover, and has a hook 12 at one end thereof adapted to be hooked through the hole 13 in the cover to which it is not permanently attached. This type of construction is particularly useful where it is desired to consult various charts mounted on cards acting as leaves. For example, it may be used by gasoline filling stations when greasing a car, there being a chart for each make 55 of car.

In order to avoid the conflicting movement of the rings, a rigid element 14 is provided at the back of the binder outside the two covers through which the rings can be threaded. The holes 15 in the rigid element through which the rings pass are preferably made a rather close fit for the latter. The rigid member 14 is shown in the drawings in the form of a strip or bar. It is movable longitudinally at the back of the binder, i. e. 60 relatively to the covers as shown at 14a in Fig. 1 of the drawings. By thus giving each ring three points of support i. e. one on each cover and one on the bar, and making each of these points of support movable independently in a direction longitudinally of the back of the book, the rings are given all the freedom that is desired and yet are always kept 65 in parallel planes. With this construction it will be obvious that the sheets or cards 70 can be turned over from one side to another of the binder when set in the form of a rack as shown in Figure 2 without jamming the sheets on the rings. In that figure a sheet 10a is shown being turned from one side of the rack to the other. It will also be noted 75 that the book can be opened to any desired degree, the novel member 14 occupying only 80 a negligible amount of space and permitting the rings to pass through it as desired.

What I claim is:

1. A loose leaf ring book having two covers, a plurality of free rings passing 95 therethrough and a member outside the two covers through which said rings pass permitting said rings to flop but maintaining them in parallel planes.

2. A loose leaf ring book comprising a 100

plurality of covers, a plurality of free rings passing through said covers and a bar lying outside said covers, said rings passing through said bar, said bar being movable
5 longitudinally of the back of the book.

3. A loose leaf ring book comprising a pair of covers, two or more free rings passing through said covers and a member extending longitudinally of the back of the
10 book on the outside thereof through which said rings pass, adapted to maintain said rings in parallel planes, said member being movable longitudinally of the back of the book and means on said covers to hold same
15 in open position at an angle of less than 180° between the outer sides thereof.

In testimony whereof I have signed my name to this specification.

HARRY B. LEWIS.
